UNITED STATES PATENT OFFICE.

WILLIAM SCHEUER, OF NEW YORK, N. Y.

DESIGN FOR A COLLAR.

47,805.

Specification for Design.

Patented Sept. 7, 1915.

Application filed May 25, 1915. Serial No. 30,473. Term of patent 3½ years.

To all whom it may concern:

Be it known that I, WILLIAM SCHEUER, a citizen of the United States, residing at New York, in the county of New York and State of New York, have invented a new, original, and ornamental Design for Collars, of which the following is a specification, reference being had to the accompanying drawing, form part thereof.

Figure 1 is a plan view of a collar in its open position. Fig. 2 is a perspective view of the collar in its closed position.

I claim:

The ornamental design for a collar, as shown.

WILLIAM SCHEUER.
